CLAIM

An ornamental design for eyeglass insert for sport sunglasses, as shown.

DESCRIPTION

FIG. 1 is a perspective view of an eyeglass insert for mounting prescription lenses, said insert connected to a pair of sport sunglasses, said sport sunglasses shown in dotted line;

FIG. 2 is a front elevation view of the design shown in FIG. 1;

FIG. 3 is a rear elevational view of the design shown in FIG. 1;

FIG. 4 is a side elevational view of the design shown in FIG. 1;

FIG. 5 is a top plan view of the design shown in FIG. 1; and,

FIG. 6 is a bottom plan view of the design shown in FIG. 1.
